UNITED STATES PATENT OFFICE.

DANIEL C. FLANIGAN, OF SEATTLE, WASHINGTON, ASSIGNOR OF ONE-FOURTH TO RHODA NESSETT, OF SEATTLE, WASHINGTON.

COMBINED MATCH-SAFE AND CIGAR-CUTTER.

No. 922,570.

Specification of Letters Patent.

Patented May 25, 1909.

Application filed June 4, 1908. Serial No. 436,690.

To all whom it may concern:

Be it known that I, DANIEL C. FLANIGAN, a citizen of the United States of America, and a resident of the city of Seattle, in the 5 county of King and State of Washington, have invented certain new and useful Improvements in Combined Match-Safes and Cigar-Cutters, of which the following is a specification.

10 My invention has particular reference to delivery safes or magazines for matches or similar articles, and the primary object thereof is the provision of an improved construction of the above type whereby a positive delivery of the article from the magazine is insured.

15 A further object is to provide efficient mechanism for operating the magazine and simultaneously effecting a clipping action.

20 Further objects and advantages will be set forth as the description progresses and the features of novelty succinctly defined in the claims.

25 In the accompanying drawing I have illustrated a preferred embodiment of my invention capable of carrying the same into successful operation.

30 With reference to the drawing, wherein similar reference numerals designate corresponding parts throughout: Figure 1 is a front end elevation of a combined clipper and delivery magazine constructed in accordance with my invention. Fig. 2 is a longitudinal vertical section of the same indicating 35 by dotted lines the relative position of the parts when nearly at the end of an active operation, and Fig. 3 is a transverse sectional view taken on line 3—3 of Fig. 2.

35 In carrying out my invention I provide a 40 magazine or casing, as 1, and a delivery member, as 2 which, as shown extends vertically through the magazine for relative sliding movement and is provided with oppositely disposed pockets in the form of recesses 3 arranged at different elevations to receive matches from respective inclined guides or bottom sections 4 of the magazine. Above the guides or feeding means 4 are guards 5 conveniently in the form of partitions which extend across the magazine 45 adjacent respective sides of member 2 and hold the matches from crowding against the same in any great mass. At opposite sides of member 2 are receivers 6 positioned exteriorly on magazine 1 at suitable elevations

and provided with deflectors 7 which serve to direct the matches to the receivers. These deflectors are conveniently in the form of covers hinged at their outer side edges to swing upwardly, as indicated in 60 Fig. 2, and provided with lugs 8 which normally engage in respective recesses provided in member 2 to effect opening movement of the deflectors as the said member moves upwardly. I preferably form member 2 with a 65 comparatively narrow projecting portion as 2' for advertising purposes and provide the recesses 6 of suitable length so that the matches delivered will have projection therefrom for more ready removal. 70

Intermediate the guides 4 and receivers 6 I have shown pressers 9 which are adapted to insure proper seating of the matches in the pockets 3. These pressers are conveniently in the form of rollers which extend across 75 respective side faces of member 2 with their end portions resting on suitable inclined tracks, as 10, provided on the side walls of the magazine. By this construction it is obvious that the pressers 9 will tend to 80 gravitate toward member 2. I prefer however that the pressers have a slight clearance relatively to such member and for this purpose I have shown suitable stops as 9' for the pressers at the inner ends of the tracks 10. 85

For operating the device I have provided movement multiplying gearing comprising rotatably mounted wheels 11, 12 and an intermediate pinion 13, meshing with wheel 11 and secured auxiliary to wheel 12, which 90 engages teeth as 14 provided on the lower portion of member 2 in the form of a rack. Meshing with wheel 11 is a rack 15 which is slidably engaged with the adjacent end wall of magazine 1 and pivotally connected as at 95 15' with a lever 16 fulcrumed at 17 on a box like casing 18 provided on a base extension of the magazine as clearly shown.

The lever 16, as shown, is in the form of a cover for casing 18 and provided with an 100 aperture 19 of suitable form to receive the tip portion of a cigar. Adjacent this aperture is a cutter 20 which is slidably supported on lever 16 for active movement across the aperture and pivotally connected with an inclined rock arm or link 21 having laterally extending pivots 22 journaled on casing 18. 105

To effect a combined clipping and feeding operation the tip portion of the cigar is inserted in aperture 19 with downward pres- 110

sure to depress lever 16 thereby forcing cutter 20 to travel forwardly and elevating rack 15. The movement of rack 15 is transmitted in an enlarged degree to member 2 through 5 the connecting gearing heretofore described and the matches in pockets 3 thereby elevated above their respective receivers 6. Should the matches project from the pockets they will be engaged by pressers 9 for proper 10 seating as member 2 moves upwardly and when lever 16 reaches the limit of its movement the resultant shock or jar dislodges the matches and they fall upon the receivers. If the jar or shock be of sufficient force to throw 15 the matches well outwardly the deflectors 7 intercept their flight and thereby insure proper delivery.

From the foregoing it will be understood that a double delivery is effected upon each 20 operation of the device and the matches presented at different elevations, consequently two persons may simultaneously withdraw matches from the receivers if desired without interfering with each other.

25 Having thus described my invention, what I claim as new, and desire to secure by Letters Patent of the United States of America, is:

1. In a device of the character described, a magazine, a discharge means projecting 30 thereinto and being slidably supported, said discharge means being formed in its opposite sides with match receiving pockets, means to slide said discharge means, and rollers arranged at the opposite sides of said discharge 35 means for insuring of proper seating of matches in said pockets during movement of said discharge means.

2. In a device of the character described, a magazine, a discharge means projecting 40 thereinto and being slidably supported, said discharge means being formed in its side with a match receiving pocket, means to slide said discharge means, tracks inclined toward said discharge means, and a roller mounted on 45 said tracks to engage and insure of the proper seating of matches in the pocket of said discharge means.

3. In a device of the character described, a magazine, a discharge member extending 50 therethrough and being supported for sliding, means to slide the same, said discharge member being formed in its opposite sides with match receiving pockets, and match receivers arranged exteriorly of said magazine 55 one above the other.

4. In a device of the character described, a magazine, a discharge member extending 60 therethrough and being supported for sliding, means to slide the same, said discharge member being formed in its opposite sides with match receiving pockets, inclined guides

in said magazines for guiding the matches into the pockets of said discharge member, vertically arranged guards on opposite sides of 65 said discharge member having their lower portions spaced from said guides, inclined tracks between said guards and said discharge member, and rollers arranged on said tracks.

5. In a device of the character described, 70 a magazine, a discharge member supported therein for sliding and provided with a toothed portion, a gear in mesh with the toothed portion of said gear including a rack bar and a lever, said lever being formed with an opening, and a cutter connected to be operated across the opening in said lever by and during movement of said lever.

6. In a device of the character described, 75 a magazine, a slidably supported discharge member, extending through the magazine and formed with a match pocket, said magazine being provided with a match receiver, a 80 swingingly supported deflector extending over said match receiver and engaged with the side of the discharge member to be operated thereby, said discharge member being 85 movable to bring its pocket into juxtaposition to the deflector, and said deflector being adapted to dislodge a match from said pocket 90 into said receiver.

7. In a device of the character described, 95 a magazine, a discharge member projecting into said magazine and being slidably supported, said discharge member being formed with a match receiving pocket, said magazine having an exteriorly arranged inclined guide for directing matches into the pocket of said discharge member, a vertical partition in said magazine spaced above said inclined guide to 100 prevent crowding of the matches about the discharge member, means in the magazine intermediate said partition and discharge member for insuring of proper seating of the matches in the pockets during movement of 105 the discharge member, and means to slide said discharge member.

8. In a device of the character described, 110 a magazine, a discharge slide projecting thereinto, said discharge slide being formed in its opposite sides with match receiving pockets, and means directly adjacent the sides and adapted to positively engage the matches when in said pockets to insure proper seating thereof in said pockets during 115 movement of said discharge means.

Signed at Seattle, Washington this 20th day of May 1908.

DANIEL C. FLANIGAN.
